ERNEST B. WRIGHT, OF NEW ROCHELLE, NEW YORK, ASSIGNOR TO HANLON & GOODMAN CO., OF NEW YORK, N. Y., A CORPORATION OF NEW YORK.

BRUSH-HOLDER.

1,277,019.

Specification of Letters Patent. Patented Aug. 27, 1918.

Application filed October 18, 1917. Serial No. 197,199.

To all whom it may concern:

Be it known that I, ERNEST B. WRIGHT, a citizen of the United States, residing at New Rochelle, in the county of Westchester and State of New York, have invented certain new and useful Improvements in Brush-Holders, of which the following is a specification.

My invention relates to brush holders for suspending paint brushes or the like in pots or pails. Such devices should be quickly adjusted for the purpose of hanging the brush in the paint pot when the brush is out of use, and should be adapted to hang the brush in such a manner that the bristles will not press against the sides or bottom of the pot and so be deformed. The holder should also be so arranged as to be out of the way when the brush is in use, so that the holder will not be in the way of the painter's hand.

The object of my present invention is to provide a holder which may be cheaply manufactured and readily mounted on the brush and which will efficiently perform the desired functions. By my invention, generally speaking, the holder is formed from sheet-metal and may comprise a member adapted to slide on the upper surface of a flat-headed brush. Or the holder may have a portion extending above the top surface of the flat-headed brush with side portions extending down on both sides of the head of the brush. In either case, a guiding slot or slots are provided with which coöperate pins mounted on the brush head, or other guiding and retaining means for the sliding holder are employed. Means for locking or latching the holder in advanced and rear positions are also provided as by forming offsets in the guiding slot or slots with which the retaining pins coact when the holder is either forward or back. The holder is provided on its forward edge with a hook portion which may rest snugly against the face of the brush head when in its backward or inoperative position.

For application to another form of brush, such as the oval or round head type of brush, the holder may be mounted on the handle of the brush and be pivoted thereto in place of being slidably mounted as in the case of the flat-headed brush. In this case, the side portions of the sheet-metal holder are pivotally secured to opposite

sides of the handle and the transverse portion of the holder which carries the hook is adapted to lie flat against the front side of the handle when the holder is in inoperative position. To permit this effect, the handle of the brush may be provided with a recess in which the hook portion of the holder may be pressed when the holder is out of use, the hook preferably being resilient and being forced into the recess to frictionally retain the holder in its inoperative position.

In order that a clearer understanding of my invention may be had, attention is hereby directed to the accompanying drawings forming part of this application and illustrating certain embodiments thereof. In the drawings, Figure 1 represents a side elevation of a flat-headed brush suspended within a paint pot, Fig. 2 is a top plan view of the brush shown in Fig. 1, Fig. 3 is a partial side elevation of a brush having a modified form of holder, Fig. 4 is a top plan view of the same, Fig. 5 is a partial side elevation of a round brush suspended in a pot by means of a modified form of holder, and Fig. 6 is a similar view to that of Fig. 5, but showing the holder in inoperative position.

Referring to the drawings, the brush shown in Figs. 1 and 2 comprises a handle 1, a rectangular head 2 and bristles 3, all of the usual type. The holder represented generally at 4 comprises a piece of sheet-metal cut or stamped to form and having a transverse portion 5 extending above the upper surface 6 of the brush head. The transverse portion 5 is provided with a forwardly extending central portion 7, at the forward end of which is the downwardly extending hook 8, which is preferably formed with downwardly and upwardly extending portions lying parallel and closely together and forming a somewhat resilient hook.

The side portions 9, 9 are bent downwardly from the ends of the transverse portion 5 and fit closely against the side surfaces of the brush head. Means are provided for coaction with side portions 9 of the holder to guide the latter and to secure the same to the brush head. Preferably, the side portions 9 of the holder are provided with forwardly extending slots 10, through which extend headed pins 11, of which there

should be two for each slot. Two of these pins may be used extending entirely through the brush head, as shown in Fig. 2, and extending through the slots in both 5 of the side portions 9 of the holder.

Slots 10 may be provided with offset portions in which the pins 11 may be slipped to lock or latch the holder in desired positions. No latch is necessary for the holder 10 when in its extreme forward position; it may, however, be desirable in some cases to lock the holder in a partly advanced position in case the adjustment is found incorrect for particular pots. For latching the holder in its rear position, the pins will 15 be aligned with offset portions 12 formed in the upper edges of the slots, so that the pins will enter these offset portions and lock the holder against forward movement, it 20 being necessary to lift the holder to free the pins from the offset portions of the slots in order to advance the holder. In this case, the hook 8 will rest snugly against the forward surface of the head of the 25 brush, when the holder is in its rear position, or, if desired, a slight recess (not shown) may be provided in the front edge of the brush head into which the hook is withdrawn when the holder is pushed back 30 into its rearmost position.

The holder is shown in its operative position in Figs. 1 and 2, in which the hook 8 is shown as extending over the upper edge of a paint pot 13. It will be noted that the 35 holder extends forwardly beyond the forward edge of the brush head a short distance only, when the holder is extended, so that the brush will be suspended in a practically vertical position in the pot with the 40 edges of the ferrules 14 on the brush head contacting the interior surface of the pot, the hook 8 engaging the outer surface of the pot adjacent its upper edge and the bristles 3 out of contact with the pot. In this form 45 of device, the holder is slidable in the direction of the long dimension of the rectangular brush head, so that a considerable number of such brushes may be hung readily within a pot. The side portions 9 of the 50 holder fit closely against the side surfaces of the brush head and transverse portion 5 of the holder is closely adjacent to the top surface of the brush head, so that the holder presents only a slight obstacle to the hand 55 of the painter, when the holder is in its back or inoperative position, with the hook 8 mounted closely against the front surface of the brush head or within a recess therein.

A modified form of holder is shown in 60 Figs. 3 and 4, in which the side portions 9 of the holder are omitted, the transverse portion 5 resting on the upper surface 6 of the brush head and being provided with a guiding slot 10' through which extend 65 the pins 11', 11', which extend downwardly

into the brush holder. Slot 10' may be provided with offset portions 15, 15 and 16, 16, into which the pins may be slipped by a lateral movement of the holder to latch the latter in its rearmost and forward positions, 70 respectively.

A further modification is illustrated in Figs. 5 and 6 in which a holder similar to that shown in Figs. 1 and 2 is mounted on the handle 1' of a brush of the round or 75 oval head type, this brush having the head 2'. In this case, the side portions 9, 9' of the holder are not provided with slots, but are pivotally mounted on a pin or pins 17. The transverse portion 5' of the holder is 80 integral with side portions 9 and joins the same together and is provided at its forward edge with the downwardly extending hook 8. The inoperative position of the holder is shown in Fig. 6, in which the transverse portion 5' of the holder is shown as lying close against the forward surface of the brush handle with the hook 8 received within a recess 18 formed in the front of the brush handle. This recess may 85 be so positioned that the hook 8 will have to be slightly forced into the same, the resilient hook yielding slightly so as to be retained therein by friction. The transverse portion 5' of the holder may, of course, be 90 given a curvature to correspond with that of the front surface of the handle 1'. When the holder is in its operative position as shown in Fig. 5, the rear edge of the transverse portion 5' may form an abutment to 100 rest against the forward edge of handle 1', the holder being swung upwardly from the position shown in Fig. 6, so that the transverse portion 5' will extend horizontally, or at some other desired angle. In this 105 case, the hook 8 should extend only a sufficient distance beyond the forward edge of the brush head 2', when the holder is in its operative position, so that the hook may be pressed over the edge of the pot to permit 110 the brush to hang in a substantially vertical position in the pot.

It should be understood that my invention is not limited strictly to the exact details of construction illustrated, but is as 115 broad as is indicated by the accompanying claims.

What I claim is:—

1. In a brush, the combination of a brush head, a holder slidably mounted thereon to slide over the upper surface thereof, said holder comprising an integral sheet having a downwardly extending hook at its forward edge adapted to extend beyond the edge of the head and over the edge of a pot when 120 extended, and having a guiding slot therethrough, and a pair of aligned pins extending through said slot into the head, said slot having offset portions to receive said pins to 125 latch the holder in a desired position. 130

2. In a brush, the combination of a brush head, a holder slidably mounted thereon to move horizontally over an upper surface thereof toward and away from an edge of the head, said holder having a downwardly extending hook at its forward edge, and guiding and retaining means secured to the head and coöperating with said holder, said holder being constructed to permit movement at an angle to its forward and back movement, at an end of its travel, into latching relation with said guiding and retaining means.
3. In a brush, the combination of a brush head, a sheet-metal holder slidably mounted thereon, having a transverse top portion above the upper surface of the head, terminating in a downwardly extending hook at the front edge, and downwardly extending side portions fitting over and slidably engaging the side surfaces of the head, and guiding and retaining means on the head,
- coöperating with said downwardly extending side portions.
4. In a brush, the combination of a frame member of the brush, a sheet-metal holder mounted thereon, having downwardly extending side portions engaging opposite sides of said frame member and a transverse portion terminating in a hook adapted to extend over the edge of a pot when the holder is in operative position, and means for movably securing said side portions to said frame member, said transverse portion being adapted to rest in contact with an exterior surface of said frame member when the holder is in inoperative position.

This specification signed and witnessed this 11th day of October, 1917.

ERNEST B. WRIGHT.
